CIRCUIT BREAKER

Jerome Sandin and Richard Hauser, Pittsburgh, Pa., assignors to Westinghouse Electric Corporation, East Pittsburgh, Pa., a corporation of Pennsylvania

Application July 31, 1946, Serial No. 687,478

17 Claims. (Cl. 200—88)

1

This invention relates to circuit interrupters and more particularly, to circuit breakers of the type used for controlling industrial power distribution and secondary network circuits.

One object of the invention is to provide a circuit breaker with a plurality of auxiliary switches which are interchangeably mounted, and which are removable from the breaker without disengaging any connections with the mechanism which operates the switches.

Another object of the invention is to provide a circuit breaker with a plurality of auxiliary switches, one of which is operated only when the breaker is automatically opened, the other switch being operated each time the breaker is opened whether manually or automatically operated, both of said switches being removable from the breaker without disengaging any connection with the mechanism which operates them.

Another object of the invention is to provide a circuit breaker with an auxiliary switch operated by a torsion spring, one end of which is directly engaged and operated by the main movable contact structure of the circuit breaker.

Another object of the invention is to provide a circuit breaker with a bell alarm switch operated by a torsion spring, one end of which is operated directly by the releasable operating mechanism of the circuit breaker.

Another object of the invention is to provide an improved means for adjusting circuit breaker auxiliary switches.

The novel features that are considered characteristic of the invention are set forth in particular in the appended claims. The invention itself, however, both as to structure and operation, together with additional objects and advantages thereof, will be best understood from the following detailed description thereof when read in conjunction with the accompanying drawings, in which:

Figure 1 is a vertical sectional view of a circuit breaker to which the invention is applied.

Fig. 2 is an enlarged plan view of a portion of the circuit breaker shown in Fig. 1 with the cover removed to show the auxiliary switches.

Fig. 3 is a sectional view taken on line III—III of Fig. 2 looking in the direction of the arrows and showing one of the auxiliary switch mechanisms.

Fig. 4 is a detail view partly in section of one of the auxiliary switches.

Fig. 5 is a vertical sectional view of a part of the breaker showing the operating mechanism.

Fig. 6 is a vertical sectional view taken on line

2

VI—VI of Fig. 2 showing one of the auxiliary switches.

Fig. 7 is a sectional view taken on line VII—VII of Fig. 4 and looking in the direction of the arrows.

Referring to Figure 1 of the drawings, the three-pole circuit breaker comprises, generally, a base 7 of molded insulating material, a cover 9 also of insulating material suitably secured to the base, operating mechanism 13, and a trip device indicated generally at 15. The casing formed by the base 7 and cover 9 is divided into three longitudinally extending compartments formed by the side walls of the casing and partition walls 14 molded integral with the base 7, and corresponding partition walls 16 molded integral with the cover 9 and cooperating with the partition walls 14. Each of the compartments is adapted to receive a stationary contact 18 and a cooperating movable contact 20 which, with corresponding terminals and connecting conductors, collectively form the three poles of the breaker. Each pole of the breaker is provided with end terminals 17 disposed in suitable openings formed in the base 7 at each end thereof.

The respective stationary contacts 18, one for each pole of the breaker, are mounted on the lower end of a conductor 21 secured, by means of a screw 23, to the base 7. At its upper end the conductor 21 is connected by means of a bolt 25 to the terminal 17.

The movable contact structures for the several poles are the same, for which reason only the one for the center pole will be described. The movable contact 20 for the center pole is secured to a contact arm 27 which is loosely supported on a channel-shaped switch-arm frame 29. The three channel-shaped frames are rigidly fastened for unitary movement by means of a metal tie bar 31 encased in an insulating tube 35 and extending across all of the poles of the breaker. The tie bar 31 is secured to the frames 29 by means of clamps 33. The channel-shaped frame 29 of the center pole is pivotally supported on a pin 37 mounted in a U-shaped main frame 39 secured by means of screws 41 to the base 7. The pivot pin 37 forms the common pivot for the three mechanically connected switch arms or frames 29.

Each of the contact arms 27, to which the movable contacts 20 are secured, is attached to its corresponding channel-shaped frame 29 by means of a headed adjusting bolt 43, threadedly engaging the channel member and locked in adjusted position by lock nuts 45. The head of the bolt 43 loosely engages an inwardly extending

flange or a sleeve (not shown) rigidly secured in a recess in the contact arm 27. A cup-shaped spring retainer 51 disposed in an opening near the upper end of the channel member 29 receives one end of a compression spring 53 having its other end engaging the contact arm 27. The spring 53, in the open-contact position of the breaker, biases the contact arm 27 counterclockwise about the head of the bolt 43, the movement being limited by a tail portion 57 of the contact arm engaging the channel member 29. In the closed position, the spring 53 provides contact pressure.

A flexible conductor 59 is electrically and mechanically connected to the lower end of the contact arm by means of a clamp 61 of magnetic material and a rivet (not shown). The lower end of the flexible conductor 59 is connected to a conductor 65 (Fig. 1) which, in turn, is connected by means of a bolt 67 to the lower terminal 17 completing the circuit through the center pole of the breaker. The circuits for the two outer poles are the same as the circuit for the center pole, for which reason, only the circuit for the center pole will be traced. This circuit extends from the upper terminal 17 through the bolt 25, conductor 21, stationary and movable contacts 18-20, contact arm 27, flexible conductor 59, conductor 65 and bolt 67 to the lower terminal 17.

When the channel member 29 moves in counterclockwise or closing direction, the arcing upper portions of the movable contacts are the first to touch the stationary contacts 18. Thereafter, as the closing movement continues, the head of the bolt 43 engages the insert in the contact arm and causes the contact arm 27 to rotate clockwise about the point of engagement of the insert with the head of the bolt 43. During the latter part of this movement of the contact arm, the face portions of the movable contacts 20 are brought into parallel engagement with the stationary contacts 18 and the arcing portion of the movable contacts thereafter disengage the stationary contacts.

The movable contact structure comprising the channel-shaped member 29, the tie bar 31 and the contact arms 27 for all of the poles of the breaker, is adapted to be operated to open and close positions by the common operating mechanism 13 (Figs. 1 to 5). This operating mechanism comprises a releasable carrier or support member 69 pivotally mounted for movement with a shaft 71 mounted in the main frame 39, a pair of toggle links 73 and 75 in interconnecting the carrier 69 and the center-pole switch arm 29, a U-shaped operating lever 77, overcenter springs 79 for connecting the operating lever 77 to the knee pivot pin 81 of the toggle 73-75, and an insulating operating handle 83 for the operating lever.

The toggle link 73 is pivotally connected by means of a pin 85 to the carrier 69 and the toggle link 75 is pivotally connected by means of a pin 87 to the channel-shaped frame 29 for the center pole of the breaker. The two legs of the operating lever 77 are disposed adjacent the inner sides of the main frame members and are pivotally supported on pins 89 projecting inwardly from said frame members. The operating handle 83 projects through a slot 91 in the cover 9 and has an arcuate protective portion 93 and side plates 95 integral with the portion 93. The side plates 95 straddle the main frame 39 and are secured to the two legs of the operating lever 77 by means

of screws 97 (only one being shown in Fig. 5) which threadedly engage the respective legs of the operating lever. The connecting portion of the operating lever is provided with a formed over portion 101. The portion 101 is for the purpose of engaging the resetting the carrier 69 to its latched position by movement of the operating handle as far as it will go in opening direction, in order to reset the trip mechanism following a tripping operation of the breaker. The carrier 69 is normally held in latched position as shown in Figs. 1 and 5 by a latch 105 of the trip device 15, which engages the latch portion 107 of the carrier.

The operation of the circuit breaker operating mechanism is described as follows: with the parts in the position shown in Fig. 1, with the contact means of all three poles of the breaker closed and the carrier 69 in latched up position; if the operating handle 83 is moved from the position shown in a clockwise direction to the opposite end of the slot 91 to rotate the operating lever 77 in a clockwise direction, the overcenter springs 79 will snap over center below the center line 81-85 and cause the toggle links 73-75 to collapse thereby causing simultaneous movement of all of the channel-shaped frames 29 and the movable contacts 20 to the open-circuit position with a snap action. To reclose the breaker, the operating handle is moved in the opposite direction back to the Fig. 1 position which movement causes the overcenter springs to snap over in the opposite direction moving the toggle to the in-toggle position thereby simultaneously closing all of the contact means with a snap action.

The circuit breaker is opened automatically in response to overload currents occurring in any pole of the breaker, by operation of the trip device 15. The trip device may be of any suitable type, preferably of the type disclosed in copending application, Serial No. 513,868, filed December 11, 1943, by G. G. Grissinger, J. Sandin and Ture Lindstrom, and assigned to the assignee of the instant invention. Such trip devices are provided with thermally-responsive means operable to release the latch 105 after a time delay in response to overload currents below a predetermined value and are also provided with electro-responsive means operable to instantaneously release the latch in response to overload currents above the predetermined value, or in response to short circuits.

When the latch 105 is released by the trip device, it frees the carrier 69 and permits the overcenter springs 79 to rotate the carrier in a counterclockwise direction about the pivot 71, thus causing collapse of the toggle 73-75 and opening of the contact means. The breaker cannot be reclosed until the operating handle has been moved to the full open position in order to reset and relatch the carrier 69 with the latch 105. After the carrier has been relatched, the operating handle may be moved to its closed position to effect closing of the contacts.

An important feature of the invention is the provision of novel auxiliary switch means and operating mechanism therefor. One auxiliary switch means, herein referred to as the bell alarm switch is operated only when the circuit breaker is automatically opened by operation of the trip device in response to overload currents and another auxiliary switch means is operated in response to movement of the main contacts each time the breaker is opened either manually or automatically.

Referring to Figs. 2 and 6 of the drawings, the trip device 15 is mounted on a base 109 which is removably mounted on the base 7 of the circuit breaker. The bell alarm switch indicated generally at 111 is mounted on a bracket 113 rigidly secured by means of screws 114 to the trip device base 109. Similarly the main contact responsive auxiliary switch, indicated generally at 115, is mounted on a bracket 117 also rigidly secured to the trip device base 109.

Both of the auxiliary switches 111 and 115 are mounted by identical means comprising threaded inserts 118 symmetrically positioned on opposite sides of the center line of the circuit breaker, so that another auxiliary switch responsive to contact movement similar to switch 115 may be substituted for the bell alarm switch 111 if desired. Both the bell alarm switch and the other auxiliary switch are removable with the trip device without making any disconnection of the switches from their respective operating means as will be described hereinafter.

Since the structure of the bell alarm switch and the auxiliary switch is the same, only one, the bell alarm switch, will be described in detail and the same reference numerals will be applied to like parts. The bell alarm switch 111 (Fig. 2) comprises two or more terminal blocks 119 of insulating material assembled between end frames 121 also of insulating material. The terminal blocks and frames are secured to the bracket 113 by means of screws 123 extending through suitable openings in the brackets 113 to 117, the end frames 121, the terminal blocks 119 and threadedly engage brackets 125 of insulating material. Each of the terminal blocks 119 have molded therein a pair of terminal contact members 127 (only one of each pair being shown for each block 119) provided with a terminal connection 129 (Fig. 4) for connecting the switch in the circuit to be controlled thereby. A slide member 131 of molded insulating material is mounted for sliding movement in openings in the end frames 121 and is biased by springs 133 to the position shown in Fig. 2. The slide 131 is provided with a projection 135 which limits its sliding movement in both directions by striking the end frames 121.

The slide 131 carries spring biased bridging contact members 137 and 139 for bridging the pairs of contacts 127. The bridging contact 137 is mounted on a rod 138 (Fig. 7) which extends upwardly through an opening in a bracket 140 secured to the slide 131 and has a cup-shaped spring retainer 142 secured to the upper end thereof. A spring 144 compressed between the retainer 142 and a similar spring retainer 146 secured to the bracket 140 biases the bridging contact 137 toward the fixed contact members 127 and provides contact pressure when the slide 131 is moved upward to engage the contacts 137 with the upper pair of contact members 127. The bridging contact 139 is similarly mounted with the exception that it is mounted above the operating fixed contacts 127 and then disposed to engage the lower pair of contacts 127 when the slide 131 is moved downward. It will be noted that with the slide 131 in the position shown in Figs. 4 and 7, the contacts 137-127 are closed and the contacts 139-127 are open so that upon downward movement of the slide 131, the contacts 139-127 will close and the contacts 137-127 will open. By assembling the bridging contacts 137 and 139 reversed and on the opposite side of the contacts 127 the contacts will

operate in reverse, that is, contacts 137-127 will be normally open and will close upon operation of the slide 131 and contacts 139-127 will be normally closed and will open upon operation of the slide 131.

The slide 131 of the bell alarm switch 111 (Figs. 2 and 6) is operated by the operating mechanism of the breaker only when it is operated in response to overload currents. It was previously described how the releasable member or carrier 69 is rotated in a counterclockwise direction when released by operation of the trip device 15. The carrier 69 is secured to the shaft 71 which rotates therewith when the carrier is released. The shaft 71 extends beyond the right-hand main frame member 39 (Fig. 2) and has secured thereto a cam member 141. The cam member 141 is provided with a groove in which is seated one end 143 of a torsion spring 145 coiled about a stud 147 mounted in the bracket 125. The other end 149 of the spring 145 bears against the upper end of the slide 131 and also engages a stop 150 on the bracket 125.

Referring to Fig. 6, when the carrier 69 is released and rotates in a counterclockwise direction, the cam member 141 rotates therewith in the same direction. During this movement, the cam 141 acts to rotate the end 143 of the spring 145 in a counterclockwise direction about the stud 147 which movement, due to the engagement of the end 149 of the spring 145 with the slide 131, biases and moves the slide downward against the tension of the springs 133 to operate the contacts 137 and 139 in the manner set forth above.

When the carrier 69 is rotated clockwise by movement of the handle 83 to the off position in order to relatch it with the latch 105, the cam member 141 is rotated therewith thereby permitting clockwise movement of the spring 145. The slide 131 and the spring 145 are then returned to their normal positions as shown in Fig. 6 by the springs 133.

The spring 145 may be adjusted relative to the slide 131 and the cam 141 by rotation of an eccentric sleeve 151 mounted on the stud 147 within the coil of the spring 145.

The construction of the auxiliary switch 115 is the same as that of the bell alarm switch with the exception that a spring 153 supported on the eccentric sleeve 151 for the auxiliary switch has one end 155 extended (Fig. 3) to be engaged and operated directly by the channel-shaped frame 29 for the left-hand pole (Fig. 2) of the breaker. The other end 157 of the spring 153 is adapted to engage and operate the slide 131 for the auxiliary switch 115.

Referring to Fig. 3 of the drawings, it will be seen that the end 152 of the spring 153 normally rests against a stop 158 and the bracket 125 and the end 155 of the spring 153 is disposed to be engaged by the channel-shaped frame 29 of the movable contact structure. The end 157 of the spring is disposed to engage the upper end of the slide 131.

When the main movable contact structure is operated to the open position, shown in dot and dash lines in Fig. 3, it operates the spring 153 in a clockwise direction and the end 157 of the spring moves the slide 131 downward to actuate the contacts 137-127 and 139-127 of the auxiliary switch. When the main movable contact structure is operated to closed position the channel-shaped frame 29 frees the spring 153 and per-

mits the springs 133 to move the slide 131 upward to its normal position.

The operating springs 145 and 153 for the bell alarm switch 111 and the auxiliary switch 115 respectively permit movement of the carrier 69 and the switch structure 29-31 to full open position after the slides 131 have reached the limit of their movement.

Both the bell alarm switch and the auxiliary switch are interchangeably mounted on the base of the trip device which is removably mounted in the breaker. The switch operating springs 145 and 153 merely press against the cam member 141 and the channel member 29 respectively thus permitting removal of the switches 111 and 115 without the necessity of disengaging any connection with the mechanism which operates them. The movable contacts of both the bell alarm switch and the auxiliary switch are mounted on insulating slides thereby eliminating the necessity of insulating links and connections.

While the invention has been disclosed in accordance with the provisions of the patent statutes, it is to be understood that various changes in the structural details thereof may be made without departing from some of the essential features of the invention.

We claim as our invention:

1. In a circuit breaker comprising relatively movable contact means and operating means releasable to cause automatic opening of said contact means, a trip device removably mounted in said breaker and operable to release said operating means, an auxiliary switch means mounted on said trip device and removable from the breaker therewith, spring means mounted on said auxiliary switch, said spring means being directly engageable by said movable contact means upon movement thereof to actuate said auxiliary switch.

2. In a circuit breaker comprising relatively movable contact means and operating mechanism releasable to cause opening of said contact means, a trip device removably mounted in said breaker and operable to cause release of said operating mechanism, auxiliary switch means mounted on said trip device and removable from the breaker with said trip device, spring means mounted on said auxiliary switch means for operating said auxiliary switch means, and means operable by said releasable operating mechanism for engaging said spring means to actuate said auxiliary switch.

3. In a circuit breaker comprising relatively movable contact means and operating mechanism releasable to cause opening of said contact means, a trip device removably mounted in said breaker and operable to cause release of said operating mechanism, an auxiliary switch means mounted on said trip device and removable from the breaker with said trip device, spring means mounted on said auxiliary switch means for operating said auxiliary switch, and means operable by said releasable operating mechanism for engaging said spring means to actuate said auxiliary switch, said auxiliary switch means, said spring means and said trip device being removable as a unit from said breaker without disengaging any connection with said operating mechanism.

4. In a circuit breaker comprising relatively movable contact means and operating means therefor, manual means for operating said operating means to effect opening and closing of said contact means, a trip device removably mounted

in said breaker and operable to cause automatic opening of said contact means, a plurality of auxiliary switch means mounted on said trip device, means comprising a spring operable by said movable contact means whenever said contact means moves to open position to actuate one of said auxiliary switch means, and a second spring operable by said operating means only on automatic opening operation to actuate another of said auxiliary switch means.

5. In a circuit breaker comprising relatively movable contact means and operating means therefor, manual means for operating said operating means to effect opening and closing of said contact means, a trip device removably mounted in said breaker and operable to cause automatic opening of said contact means, a plurality of auxiliary switch means mounted on said trip device, means comprising a spring operable by said movable contact means whenever said contact means moves to open position to actuate one of said auxiliary switch means, and a second spring operable by said operating means only on automatic opening operation to actuate another of said auxiliary switch means, and said trip device, said auxiliary switch means and said spring means being removable from said breaker as a unit.

6. In a circuit breaker comprising relatively movable contact means and operating means therefor, manual means for operating said operating means to effect opening and closing of said contact means, a trip device operable to cause automatic opening of said contact means, a plurality of auxiliary switch means, one of said auxiliary switch means being operable by said movable contact means whenever said contact means moves to open position, and the other of said auxiliary switch means being operable by said operating means only on automatic opening operation, and both of said auxiliary switch means being mounted by identical but oppositely positioned mounting means on said trip device.

7. In a circuit breaker comprising relatively movable contact means and operating mechanism therefor, a releasable member operable when released to cause automatic opening of said contact means, a trip device removably mounted in said breaker and operable to release said releasable member, an auxiliary switch device mounted on said trip device and removable therewith from said breaker, means comprising a torsion spring mounted on said auxiliary switch device for actuating said auxiliary switch, means comprising a part movable with said releasable member and operable upon release of said releasable member to engage and actuate said torsion spring, said torsion spring being removable from the breaker with said auxiliary switch device without disengaging any connection with said part.

8. In a circuit breaker comprising relatively movable contact means and operating mechanism therefor, a releasable member operable when released to cause automatic opening of said contact means, a trip device removably mounted in said breaker and operable to release said releasable member, an auxiliary switch device mounted on said trip device and removable therewith from said breaker, means comprising a torsion spring mounted on said auxiliary switch device for actuating said auxiliary switch, means comprising a part movable with said releasable member and operable upon release of said releasable member to engage and actuate said torsion spring, said torsion spring being removable from the breaker

with said auxiliary switch device without disengaging any connection with said part and operating means for adjusting said torsion spring relative to said auxiliary switch and said part.

9. In a circuit breaker comprising relatively movable contact means and operating mechanism therefor, a releasable member operable when released to cause automatic opening of said contact means, a trip device removably mounted in said breaker and operable to release said releasable member, an auxiliary switch device mounted on said trip device and removable therewith from said breaker, means comprising a torsion spring mounted on said auxiliary switch device for actuating said auxiliary switch, means comprising a part movable with said releasable member and operable upon release of said releasable member to engage and actuate said torsion spring, said torsion spring being removable from the breaker with said auxiliary switch device without disengaging any connection with said part and means comprising an eccentric sleeve operable to adjust the position of said torsion spring.

10. In a circuit breaker comprising relatively movable contacts, a switch arm operable to open and close said contacts, a trip device removably mounted in said breaker and operable to cause opening movement of said switch arm, an auxiliary switch mounted on said trip device and removable therewith from said breaker, means comprising a torsion spring having one end operatively related to said auxiliary switch, the other end of said torsion spring being directly engageable by said switch arm when said switch arm moves to open said contacts to operate said auxiliary switch.

11. In a circuit breaker comprising relatively movable contact means and operating means therefor including a member releasable to cause automatic opening of said contact means, a trip device operable to cause release of said releasable member, auxiliary switch means, a pivot on said auxiliary switch means, means comprising a torsion spring rotatably mounted on said pivot and having one end operatively related to said auxiliary switch means, means movable with said releasable member operatively related to the other end of said torsion spring, said movable means when released rotating said torsion spring about said pivot to actuate said auxiliary switch means, and adjusting means on said pivot for adjusting said torsion spring relative to said movable member and said auxiliary switch means.

12. In a circuit breaker comprising relatively movable contact means and operating means therefor including a member releasable to cause automatic opening of said contact means, a trip device operable to cause release of said releasable member, auxiliary switch means, means comprising a torsion spring having one end operatively related to said auxiliary switch means, means movable with said releasable member operatively related to the other end of said torsion spring, and said movable means when released operating said torsion spring to actuate said auxiliary switch means and means for adjusting the position of said torsion spring relative to said auxiliary switch means and said movable member.

13. In a circuit breaker comprising relatively movable contact means and operating means therefor including a member releasable to cause automatic opening of said contact means, a pivot for supporting said releasable member, a trip device operable to cause release of said pivoted member, auxiliary switch means, a torsion spring

having one end operatively related to said auxiliary switch means, eccentric means on said auxiliary switch means mounting said torsion spring for rotary movement, means on said pivot engaging the other end of said torsion spring and operable upon release of said releasable member to operate said spring to actuate said auxiliary switch means, and adjusting means for adjusting said eccentric means to vary the position of said torsion spring.

14. In a circuit breaker comprising relatively movable contact means and operating means therefor including a pivoted member releasable to cause automatic opening of said contact means, a pivot for supporting said releasable member, a trip device operable to cause release of said pivoted member, auxiliary switch means, means comprising a spring having one end abutting against said auxiliary switch means, means mounting said spring for rotary movement, a lateral extension on said pivot, and cam means on said extension engaging the other end of said spring and operable upon release of said releasable member to rotate said spring about said mounting means to actuate said auxiliary switch means.

15. In a circuit breaker comprising relatively movable contact means, a switch arm operable to open and close said contact means, operating means comprising a member releasable to cause automatic opening movement of said switch arm, a pivot for pivotally supporting said releasable member, a trip device removably mounted in said circuit breaker and operable to cause release of said releasable member, auxiliary switch means comprising a plurality of auxiliary switches mounted on said trip device, a first torsion spring having one end associated with one of said auxiliary switches the other end of said torsion spring being directly engageable by said switch arm for operating said one auxiliary switch in response to movement of said switch arm, a second torsion spring having one end associated with another of said auxiliary switches, means on said pivot engaging the other end of said second torsion spring and operable upon release of said releasable member for operating said second torsion spring to actuate said other auxiliary switch in response to movement of said releasable member.

16. In a circuit breaker comprising relatively movable contact means, a switch arm operable to open and close said contact means, operating means comprising a member releasable to cause automatic opening movement of said switch arm, a pivot for pivotally supporting said releasable member, a trip device removably mounted in said circuit breaker and operable to cause release of said releasable member, auxiliary switch means comprising a plurality of auxiliary switches mounted on said trip device, a first torsion spring having one end associated with one of said auxiliary switches the other end of said torsion spring being directly engageable by said switch arm for operating said one auxiliary switch in response to movement of said switch arm, a second torsion spring having one end associated with another of said auxiliary switches, means on said pivot engaging the other end of said second torsion spring and operable in response to movement of said releasable member for operating said second torsion spring to actuate said other auxiliary switch, said auxiliary switch means and said torsion spring being removable from the breaker with said trip device without disengaging any connections with said switch arm or said releasable member.

17. A circuit breaker comprising operating means for opening and closing said breaker, a trip device removably mounted in said breaker and operable to effect operation of said operating means, auxiliary switch means mounted on said trip device and removable therewith from said breaker, actuating means for said auxiliary switch means comprising a torsion spring mounted on said auxiliary switch device, means comprising a portion of said operating means for engaging and actuating said torsion spring, and said torsion spring being removable with said auxiliary switch device without disengaging any connection with said portion of said operating means.
